HANDLING AND STORAGE TRAY FOR SILICON WAFERS

Dale E. De Rousse, 1103 Royal Ann Court,
Sunnyvale, Calif. 94087

Filed Mar. 6, 1967, Ser. No. 6,060

Term of patent 14 years

(Cl. D87—1)

FIG.1

FIG.2

FIG.6

FIG.3

FIG.5

FIG.4

FIG. 1 is an exploded perspective view of a handling and storage tray for silicon wafers showing my new design;

FIG. 2 is a plan view of FIG. 1;

FIG. 3 is a side elevational view of FIG. 1, the reverse side being a mirror image thereof;

FIG. 4 is a bottom view of FIG. 1;

FIG. 5 is an end view of FIG. 1, the opposite end being a mirror image thereof; and

FIG. 6 is a top plan view thereof of FIG. 1, the cover having been removed for purposes of illustration.

I claim:

The ornamental design for a handling and storage tray for silicon wafers, as shown and described.
